UNITED STATES PATENT OFFICE

GEORGE W. TOFT, OF MOUNTAIN VIEW, CALIFORNIA

FALSE TOOTH

Application filed August 8, 1928. Serial No. 298,327.

My invention relates to improvements in false teeth, and it consists in the combinations, constructions and arrangements hereinafter described and claimed.

5 Porcelain teeth of the type shown in the drawing at present are secured in place to a plate and the plate in turn is anchored to adjacent teeth. The way of securing the tooth to the plate is by providing a groove 10 or slot in the porcelain tooth and sliding a key carried by the plate into the groove. The groove is relatively deep, because the top of the groove is reduced for providing lips for engaging with the neck of the key, 15 and these lips must be thick enough to secure the tooth to the plate. The tooth is very likely to crack along the line coinciding with the slot.

The principal object of the present invention is to provide a tooth in which the groove is far more shallow than the standard one now on the market, and in which a more permanent connection is made between the tooth and the supporting plate. The shallow groove provides a stronger tooth, and therefore such a tooth will not crack so readily.

Other objects and advantages will appear as the specification proceeds, and the novel 30 features will be particularly pointed out in what I hereinafter claim.

My invention is illustrated in the accompanying drawing forming a part of this application, in which

35 Figure 1 is a plan view looking at the inner face of the tooth;

Figure 2 is a section along the line 2—2 of Figure 1 showing the plate in position;

40 Figure 3 is a side elevation of the tooth showing it operatively applied to the plate; and

Figure 4 is a perspective view of the plate and key.

In carrying out my invention, I show a 45 tooth A, a plate B, and a key C. The tooth A is shaped to resemble an ordinary tooth. The inner face 1 thereof is smooth and is provided with a groove 2 that extends downwardly into an inclined face 3 of the tooth. 50 The groove has an enlarged portion 4 and

an opening smaller in width than the portion 4. This provides lips 5 that are very small. These lips extend the entire length of the groove and engage with the neck portion 6 of the key C.

55 The key has an enlarged portion 7 that is snugly received in the portion 4 of the groove. The key is secured to the plate B by any means (not shown).

60 The thinning of the lips 5 does away with the necessity of having the enlarged portion 4 extend so far into the tooth A as is the case where thick lips are provided. Up to the present time, thick lips have had to be provided in order to give the porcelain 65 forming the lips the necessary body structure to withstand the strain. In the present invention I use thin lips for the porcelain and reinforce these with pins 8 or other suitable reinforcing means.

70 Figure 1 shows these pins as being staggered, but it is obvious that they can be disposed opposite each other and in the same plane without departing from the spirit and scope of my invention.

75 Figure 2 shows how the pins extend into the body of the tooth and how these are provided with recesses 9 for receiving the enlarged portion 7 of the key. The inner ends of the members 8 may be enlarged as 80 at 10 for aiding and anchoring the members. As many members as necessary may be provided. The drawing shows two.

85 From the foregoing description of the various parts of the device, the operation thereof may be readily understood.

90 The plate B is anchored in place in the usual manner, and then the false tooth is slipped down over the key C and is held in place by cement. The amount of porcelain 95 between the bottom of the groove 2 and the face 11 is relatively great, and therefore the tooth will have less tendency to split along the groove than is now the case. The lips 5 will hold the tooth to the key and the plate because these lips are reinforced by the members 8. In fact, the members 8 do practically all of the connecting between the tooth and the plate, the lips 5 merely 100 acting as guides.

The pins in the porcelain permit making the groove and neck portion much smaller than without them, thus giving greater bulk of porcelain over the groove. The inherent strength of the pins prevent breakage at the neck portion.

The pins in the porcelain are to be as small in bulk as possible, yet large enough to give the required strength. Any metallic element has a tendency to weaken porcelain in proportion to its bulk and in the direction of its long axis. Hence the pins may not necessarily be placed directly opposite each other.

15 Although I have shown and described one embodiment of my invention, it is to be understood that the same is susceptible of various changes, and I reserve the right to employ such changes as may come within 20 the scope of the invention as claimed.

I claim:

1. A false tooth having a groove and reinforcing pins extending transversely to the groove and being embedded in the tooth, the pin disposed on one side of the groove being staggered with respect to the pin on the other side.

2. A false tooth having a groove on its inner surface, the groove being enlarged inwardly for forming thin lips, and metal pins embedded in the tooth and extending transversely to the groove, said pins having recesses conforming to the enlarged portion of the groove, said pins being staggered with respect to each other.

3. A false tooth having a groove on its inner surface, the groove being enlarged inwardly for forming thin lips, and metal pins embedded in the tooth and extending transversely to the groove, said pins having recesses conforming to the enlarged portion of the groove, said pins being staggered with respect to each other, and a plate having a key receivable in the groove, said key having a cross section similar to the cross section of the groove.

4. A porcelain false tooth having a longitudinally extending groove with thin lips projecting toward each other, and pins disposed on each side of the groove and being embedded in the tooth for reinforcing the lips.

5. A porcelain false tooth having a longitudinally extending groove with thin lips projecting toward each other, and pins disposed on each side of the groove and being embedded in the tooth for reinforcing the lips, the pin disposed on one side of the groove being staggered with respect to the pin on the other side.

6. A porcelain false tooth having a longitudinally extending groove with thin lips projecting toward each other, pins disposed on each side of the groove and being embedded in the tooth for reinforcing the lips,

and a supporting member having a tongue removably receivable in the groove.

7. A porcelain false tooth having a longitudinally extending groove with thin lips projecting toward each other, pins disposed on each side of the groove and being embedded in the tooth for reinforcing the lips, the pin disposed on one side of the groove being staggered with respect to the pin on the other side, and a supporting member having a tongue removably receivable in the groove.
